(57) **CLAIM**

The ornamental design for a conduit support, as shown and described.

DESCRIPTION

FIG. 1 is an isometric elevational view of a conduit support with a telescoping support in broken lines showing our new design;

FIG. 2 is a front view of the conduit support of FIG. 1; FIG. 3 is a left side elevational view of the conduit support of FIG. 1 with the right side elevational view being a mirror image thereof;

FIG. 4 is a top view of the conduit support of FIG. 1; and, FIG. 5 is a bottom view of the conduit support of FIG. 1. The broken lines showing nuts, washers, and support members in FIGS. 1-5 depict an environment for illustrative purposes only and form no part of the claimed design.
